UNITED STATES PATENT OFFICE.

FRANCIS W. BOURGOIN, OF ST. LOUIS, MISSOURI.

CRISPETTE-MACHINE.

1,232,192.

Specification of Letters Patent.

Patented July 3, 1917.

Application filed November 14, 1916. Serial No. 131,266.

To all whom it may concern:

Be it known that I, FRANCIS WALTER BOURGOIN, a citizen of the United States, and a resident of the city of St. Louis, in the State of Missouri, have invented an Improvement in Crispette-Machines, of which the following is a specification.

My invention is an improvement in crispette machines, and has for its object to provide a machine of the character specified, wherein a plurality of molds is provided and a plunger coöperating therewith, the molds being mounted in a carriage to be moved in alternation beneath the plunger, and wherein an ejecting means is provided controlled by the movement of the plunger for ejecting the formed crispettes, and wherein the movement of the plunger also controls the moving of the carriage.

In the drawings:

Figure 1 is a side view of the improved machine.

Fig. 2 is a similar view with the parts in another position and with parts in section.

Figs. 3 and 4 are sections on the lines 3—3 and 4—4 of Fig. 1.

Fig. 5 is a front view of the pawl and ratchet connection.

Fig. 6 is a section on the line 6—6 of Fig. 5.

In the present embodiment of the invention a suitable table 1 is provided, and a portion of the top of the table is cut away at the center thereof, leaving merely a frame. The frame at the upper edge of the opening is rabbeted to receive a plate 2, and beneath this plate is arranged a casing 3 and beneath the casing is arranged a suitable heater 4 for heating the air in the casing. The casing has a cold air inlet 5, and a discharge outlet 6, which communicates with a suitable chute 7 at the under side thereof for delivering the crispette material to the molds to be described.

Above the table is mounted a carriage 8, the carriage being movable longitudinally of the table by mechanism to be later described, and the carriage travels in guides 9 arranged at opposite sides of the table and supported by brackets 10 connected with the table. The space between the guides and the table top is inclosed by a species of casing 11, and the molds 12 are supported by

the carriage, the said carriage having threaded openings to receive the molds.

In the present instance two molds are provided, the said molds being merely open ended cylindrical receptacles whose bottoms move near the table top 2. The molds are spaced apart from each other, and at the outer side of each mold, also connected with the carriage, is a guide casing 13, said casings being open cylindrical receptacles engaging at their upper ends threaded openings in the carriage. The carriage is adapted to be reciprocated in the guides, by mechanism to be later described, to bring the molds in alternation beneath a plunger indicated at 14 and at the opposite sides of the plunger discharging chutes 15 lead from openings in the table top, the said chutes being in position such that the mold not beneath the plunger will register with one of the chutes.

Referring to Fig. 2 it will be seen that the mold at the right registers with the chute at the right, and it will be evident that when the mold at the right is brought into register with the plunger, the mold at the left will be in register with the chute 15 at the left.

The plunger 14 is a hollow cylindrical casing adapted to contain melted butter, and the said casing is of a size to fit within the molds. A feed casing 16 encircles the plunger, and the mold is slidably mounted with respect to said casing and the chute 7 before-mentioned delivers to the said casing, an opening 17 being provided in the casing at the bottom of the chute. When the plunger is raised with respect to the casing 16, in a manner to be presently described, a portion of pop corn may be fed through the opening 17 into the mold 12 which is below the plunger. When now the plunger descends, it will be evident that the pop corn will be compressed into a crispette within the mold, being held at one end by the table top 2 and at the other by the bottom of the mold. The melted butter which may pass through the openings 14a in the plunger wall and in the bottom thereof will thoroughly lubricate the mold and casing 16, so that the plunger will not stick to the pop corn or to the mold. When the plunger is again lifted out of the mold, the table is

moved a sufficient distance to bring the other mold in place beneath the plunger, and to bring that mold which carries the crispette over a discharge chute 15.

5 Ejecting mechanism is provided, controlled by the movement of the plunger, the said mechanism comprising rods 18 having heads at their lower ends, the rods moving through guides 19 arranged above the carriage and connected with the guides 9. The 10 plunger has threaded into the upper end thereof a plug 20, and a cross head 21 is pivoted to this plug. The ends of the cross head are pivoted to the rods 18, and a pair 15 of links 22 and 23 connect the cross head with the operating lever 24 for the plunger. The lever is pivoted at one end to an up-standing bracket arm 25 from the table, the said arm being braced against the table by 20 an inclined brace 26, and it will be evident that when the lever is lifted, as indicated by the arrow in Fig. 1, the plunger 14, the head 21, and the rods 18 will also be lifted. As 25 soon as the plunger and the ejecting rods have cleared the carriage, the carriage is moved, and the movement of the plunger controls the moving of the carriage.

An elbow lever consisting of portions 27 and 28 is pivoted at the pivotal connection 30 of the lever 24 with the bracket 25, and the portion 27 of the said lever has a toothed segment 29, which engages a pinion 30 on a shaft 31. This shaft is held in a bearing on the bracket 25, and a ratchet wheel 32 is 35 arranged on the shaft adjacent to the pinion, the ratchet wheel being secured to the pinion. A disk 33 is mounted on the shaft outside of the ratchet wheel, and this disk has a marginal flange inclosing the ratchet 40 wheel. Pawls 34 are pivoted to the disk, and the said pawls are spring pressed toward the ratchet wheel. When the pinion is rotated in one direction the disk 33 will be rotated while when the pinion is rotated in the opposite direction the pawls will slip idly over the ratchet wheel. A pitman 35 connects the disk with the carriage in such manner that when the disk is rotated the carriage will be reciprocated.

50 The portion 28 of the elbow lever extends above the lever 24, and the said portion has a lateral lug 36 which overlies the lever 24 and is adapted to be engaged thereby at the moment when the plunger 14 clears the carriage. A guide loop 37 is connected with the lever and engages over the arm 28 of the elbow lever, and it will be evident that when the lever engages the lug 36 and is moved a trifle farther upward, the pinion 30 55 will be rotated to cause the table to be moved from the position shown in Fig. 2 to a position such that the mold at the left will register with the chute 15 at the left, and with the ejector 18 at the left. When now 60 the plunger is moved downward to form a

crispette in the mold at the right, the crispette in the mold at the left will be ejected, and the ejector 18 at the left will move in the guide casing 13 at the left.

The feed casing 16 is anchored to the carriage during the movement of the plunger into the mold, by means of a gravity lock indicated at 38, the said lock being in the form of a rod mounted to move in guide lugs 39 on the casing 16. The lower end of the 75 rod is adapted to engage openings 40 in the carriage at the respective molds, the said opening being so positioned that when the rod engages the same the casing will be directly above a plunger.

80 A latch 41 is pivoted within a recess 41^a in the plunger, and this latch extends through a vertical slot 16^a in the feed casing 16 and is adapted to engage a lug 42 on the locking rod. The lower end of the latch 41 is normally held in extended position by a spring which encircles the pivot pin of the latch. It will be noticed that just above the catch of the latch is a cam shaped portion, which is adapted to engage the upper end 90 of the slot in the feed casing 16 in which the latch moves, to release the latch. When the plunger rises, the latch engages the lug 42, and lifts the latch bar. The plunger, by this time, is out of the mold, and a further slight raise lifts the latch bar 38 out of the opening 40. A further movement of the plunger causes the cam shaped portion of the latch to engage the upper end of the slot in the feed casing and the latch bar is released, dropping on to the carriage and engaging the other opening 40 when the parts are in proper position. The latch 41 is so arranged, that it will not engage the lug 42, until the moment before the lower end of 105 the plunger clears the top of the mold. The slight farther movement of the plunger will lift the latch to free the carriage. The farther upward movement of the lever 24 to operate the elbow 27-28 lifts the plunger 110 far enough to permit a new supply of material to pass through the opening 17. The casing 16 is connected with the guides 19, by means of braces 44.

115 In operation, with the parts in the position of Fig. 2, the plunger is about to descend into the mold. During the descent of the plunger the pawls 34 slip idly over the ratchet wheel 32. A crispette is formed, and the plunger is again lifted into the position 120 of Fig. 2. At this moment both plunger and ejector are clear of the carriage, and the lever 24 engages the elbow lever 27-28, and the table is reciprocated, to move the mold at the left into position beneath the ejector at the left, and to move the mold at the right into position beneath the plunger. At the same time a charge of pop corn is fed into the mold. The plunger moves downward, and before it begins to move into the mold 125

the latch 38 is released to lock the carriage to the casing 16. As the plunger moves into the mold to compress the charge of pop corn, the charge already compressed in the other mold is ejected. The heater 4 retains the butter in the plunger in melted condition, and retains the candy on the pop corn in a condition soft enough to insure the proper formation of the crispette.

19 It will be understood that the downward movement of the operating lever 24 returns the elbow lever 27-28 to original position, that is to the position shown in Fig. 1, because of the loop 37.

15 I claim:

1. A crispette machine comprising in combination, a table, a carriage mounted to reciprocate longitudinally above the table, the table having guides for the carriage, molds carried by the table, a feed casing arranged above the carriage and held by the guides, means for delivering material to the feed casing, means for heating the said material, a plunger mounted to move in the feed casing, ejectors carried by the plunger for ejecting the crispettes from the molds when the molds are out of register with the plunger, said table having a discharge chute at each ejector, said plunger being adapted to contain a lubricant and having openings for delivering the same to the molds, latch mechanism for anchoring the carriage to the feed casing, means for operating the plunger, means controlled by the movement of the plunger for engaging and releasing the latch mechanism, and means controlled by the movement of the plunger for reciprocating the carriage to bring the molds in alternation beneath the plunger.

40 2. A crispette machine comprising in combination, a table, a carriage mounted to reciprocate longitudinally above the table, the table having guides for the carriage, molds carried by the table, a feed casing arranged above the carriage and held by the guides, means for delivering material to the feed casing, means for heating the said material, a plunger mounted to move in the feed casing, ejectors carried by the plunger for ejecting the crispettes from the molds when the molds are out of register with the plunger, said table having a discharge chute at each ejector, latch mechanism for anchoring the carriage to the feed casing, means for operating the plunger, means controlled by the movement of the plunger for engaging and releasing the latch mechanism, and means controlled by the movement of the plunger for reciprocating the carriage to bring the molds in alternation beneath the plunger.

55 3. A crispette machine comprising a table, a carriage having guided reciprocating movement above the table and carrying a plurality of open ended molds, a fixed feed casing above the carriage, a plunger mount-

ed to reciprocate within the feed casing, means for feeding material to the feed casing, means controlled by the movement of the plunger into upward position for reciprocating the carriage to bring the molds in alternation beneath the plunger, means for latching the carriage to the feed casing when the mold is beneath the same and controlled by the movement of the plunger, and ejecting means controlled by the movement of the plunger for ejecting the crispettes from the molds when the molds are not beneath the plunger.

4. A crispette machine comprising a table, a carriage having guided reciprocating movement above the table and carrying a plurality of open ended molds, a fixed feed casing above the carriage, a plunger mounted to reciprocate within the feed casing, means for feeding material to the feed casing, means controlled by the movement of the plunger for reciprocating the carriage to bring the molds in alternation beneath the plunger, means for latching the carriage to the feed casing when the mold is beneath the same and controlled by the movement of the plunger.

5. A crispette machine comprising a table, a carriage having guided reciprocating movement above the table and carrying a plurality of open ended molds, a fixed feed casing above the carriage, a plunger mounted to reciprocate within the feed casing, means for feeding material to the feed casing, and means controlled by the movement of the plunger for reciprocating the carriage to bring the molds in alternation beneath the plunger.

6. A crispette machine comprising a table, a mold carriage provided with open ended molds having guided reciprocating movement above the table, a plunger mounted to move into and out of the molds when they are in position beneath the plunger, means for guiding the plunger, means controlled by the movement of the plunger into upward position for reciprocating the carriage to bring the molds in alternation beneath the plunger, said means for guiding the plunger being adapted for delivering material to the molds when they are beneath the plunger, and means controlled by the movement of the plunger for anchoring the said means to the carriage.

7. A crispette machine comprising a table, a mold carriage provided with open ended molds having guided reciprocating movement above the table, a plunger mounted to move into and out of the molds when they are in position beneath the plunger, means for guiding the plunger, means controlled by the movement of the plunger into upward position for reciprocating the carriage to bring the molds in alternation beneath the plunger, and means controlled by the movement of the plunger for anchoring the said means to the carriage.

movement of the plunger for ejecting the crispettes from the molds when they are away from position beneath the plunger.

8. A crispetto machine comprising a table, a mold carriage provided with open ended molds having guided reciprocating movement above the table, a plunger mounted to

move into and out of the molds when they are in position beneath the plunger, means for guiding the plunger, and means controlled by the movement of the plunger for reciprocating the carriage to bring the molds in alternation beneath the plunger.

FRANCIS W. BOURGOIN.
